UNITED STATES PATENT OFFICE.

HARRIET L. MERRIAM, OF PITTSBURG, PENNSYLVANIA, ASSIGNOR TO
CARNEGIE INSTITUTE, A VOLUNTARY ASSOCIATION.

DESIGN FOR A BADGE.

No. 38,749.

Specification for Design.

Patented Aug. 20, 1907.

Application filed January 25, 1907. Serial No. 354,124. Term of patent 14 years.

To all whom it may concern:

Be it known that I, HARRIET LAMONT MERRIAM, a citizen of the United States, residing at Pittsburg, in the county of Allegheny and State of Pennsylvania, have invented a new, original, and ornamental Design for Badges, of which the following is a specification, reference being had to the accompanying drawing, forming a part thereof.

The leading feature of my design for a badge consists of a diamond-shaped body portion, in the center of which are the letters

"C T S," the background between the edge of the diamond and the monogram being filled in with conventional lines of various colors, positioned parallel with the perimeter of the diamond-shaped body.

I claim:

The ornamental design for a badge as shown.

HARRIET L. MERRIAM.
